CAPSTAN BLOCK

Carl O. Bruestle, Rahway, N. J., assignor to
 Elevator Supplies Company, Incorporated,
 Rahway, N. J., a corporation of New Jersey

Application September 12, 1939, Serial No. 294,459

3 Claims. (Cl. 205—20)

This invention relates to improvements in capstan blocks or pulleys for wire drawing machines and the like, and provides improvements therein.

In these machines, there is usually a plurality of drawing dies, with a block for each die. The peripheral speed of the blocks is progressively greater in sequence with the dies in consequence of the increments of wire-speed due to elongation as the wire passes through each die. The machines, particularly those for drawing the smaller sizes of wire, are designed however so that there is a certain amount of slip between each capstan block and the wire. This is to prevent the full pulling force of the block being exerted on any flight of wire between a die and a block, which would be apt to break the wire. At the same time the amount of slip must be limited, particularly in high speed machines, so as to avoid "burning," abrading, etc. of the wire. The blocks are usually made with a plurality of drums or pulleys mounted on a single spindle, the drums being of different diameter to give the different peripheral speeds desired.

The aforesaid slip causes wear and grooving of the drums or pulleys. They can stand only a certain amount of refinishing before the diameter is reduced to a degree where the slip becomes excessive. Moreover, refinishing the blocks is comparatively expensive and necessitates the machines being idle for a day or so.

The present invention provides a means by which worn surfaces of blocks or pulleys can be quickly and inexpensively replaced, a true cylindrical form and a firm solid bearing surface maintained, and which conform to the conditions of operation, such as heat expansion, torque conditions etc. in a way to provide a pulling surface which does not detrimentally affect the wire running thereon.

An embodiment of the invention is illustrated in the accompanying drawing, wherein:

Fig. 1 is a transverse section through the block and the spindle.

Fig. 2 is a plan view of a strip facing the block, on which the wire makes contact and which sustains the wear.

Fig. 3 is a side elevation of the strip shown in Fig. 2 in the form of a circle.

Figs. 4 and 5 are respectively, a side elevation and vertical section of one of the cheek plates forming a part of the capstan block.

Referring to said drawing, numeral 10 indicates a rotary spindle, which is driven by means not shown. A pulley or block 12 is secured on the spindle 10 so as to rotate therewith. The

block 12 may have one or more cylindrical portions constituting the drums or pulleys around which the wire runs. Three such cylindrical portions 14, 15 and 16 are shown. The wire does not contact directly with the cylindrical portions 14, 15, 16 but with tires 18, 19 and 20. These tires are strips 25 of hardened steel or the like, which encircle the cylindrical portions 14, 15 and 16 and fit closely and firmly thereon.

The strips 25 have a length corresponding very closely to the circumference of the surface of the cylindrical portion 14, 15, or 16 on which they rest, and are preferably formed as very true circles. The ends 26, 27 of the strip 25 do not quite meet, and when secured in place on the cylindrical surface 14, 15, 16 of the drum do not quite abut, a gap on the order of a few thousandths of an inch or so being left between the ends. The outer edges of the strips at the ends are also slightly rounded so as to remove any burrs and to dull the edge. The ends 26, 27 are not connected in use, and the width of the gap between these ends 26, 27 should be such that expansion of the strip by heat brings the ends just about together without one end being forced against the other. Thereby the arrangement is such that the expansion of the strip by heat will not bring about a reaction of forces between the ends which will tend to force the strip from close contact with the surface of the cylindrical portion 14, 15 or 16 on which it rests, and thereby get out of round even slightly.

Means are provided for fastening the strips 25 firmly to the block, so that they will firmly withstand slipping on the block against the comparatively strong torque which is exerted through the spindle and block, against the pull of the wire thereon which is being drawn through a die. For this purpose an edge of the strip may be provided with one or more notches 30. Matching these notches 30 are projections or pins 33 on the block. The projections or pins fit closely in the notches 30, and hold the strip 25 firmly against the torque of the block.

In order to provide a smooth surface on which the wire may run, and also to avoid any crevices between the block and the circumferential edges of the strips in which wires of small diameter may catch the circumferential edges of the strip 25 are fitted into lateral grooves in the block facing each edge of a strip. In order to readily replace worn tires or strips 25 a cheek piece 36 is provided which is capable of being moved axially with relation to a side of a pulley or block. In a stepped pulley or block such as here

shown, the intermediate cheek pieces 37, 38 are grooved on two sides, thereby performing the dual function of receiving the adjacent edge portions of the two strips 25 corresponding to the diameters of two cylindrical portions 14, 15, 16. The notched marginal portions of the tire strips are thereby covered by the grooved portions of the block or cheek-pieces. The grooves have diameters corresponding to those of the tire strips which fit into them. The wall of each groove which lies closest to the axis of the drum has a diameter which is less than the diameter of the cylindrical portion of the drum (14, 15 and 16) on which the tire strip rests, so that under all conditions the tire strip is seated firmly and solidly against the aforesaid cylindrical portion. This condition may be obtained by undercutting each groove, as shown.

The intermediate cheek pieces 37, 38 are illustrated, in Figs. 4 and 5. These cheek pieces, 37 for example, have a central opening 40 having a diameter corresponding to the diameter of one of the cylindrical portions of the block, as for example the cylindrical portion 14. Adjacent the opening 40 is a circular groove 42 corresponding in width to the thickness of the strips 25, and having a depth slightly greater than the depth of the notches 30 in the strip. The groove 42 serves to receive and confine the notched edge 30 of the strip and the notched marginal portions of the tire strips are thereby covered by the cheek-piece. The cheek pieces adjacent the opening 40 also have semi-circular grooves 44 therein which register with and fit over the pins or projections 33 which project into the notches 30 of the strip 25. The intermediate cheek pieces, as for example the piece 37, have outer peripheral portions 46 which have a diameter somewhat greater than that of the diameter of the step next to that on which it bears and which acts as a cheek at the side of the pulley or drum. In this peripheral portion 46, on the side of the cheek piece which is opposite to that which has the groove 42 formed therein is another groove 50 having a maximum diameter corresponding to the diameter of a strip 25 resting firmly against a cylindrical portion of the block, as the cylindrical portion 15. The groove 50 receives and confines an edge of the strip 25, which may be an unnotched edge thereof. This groove is also somewhat undercut, as illustrated and heretofore described, to facilitate the assembly of the parts and the firm bearing of the tire-strip on the cylindrical portion of the drum. The cheek piece 38 has a central opening 40 of larger diameter than that in the cheek piece 37, to enable it to fit on the cylindrical portion 15 which is of larger diameter than the cylindrical portion 14; otherwise it may be similar in construction to that of the cheek piece 36. The central opening 53 of the cheek piece 36 may have a diameter corresponding to that of the spindle 12, and in assembled position may rest thereon. This cheek piece 36 is provided with a groove 55 into which the edge of the strip 25 which bears on the cylindrical portion 14, projects, and by which it is confined. This cylindrical groove 55 is also somewhat undercut similarly to the groove 50 of the cheek pieces 37, 38. For convenience in manufacture, the block 12, adjacent the cylindrical portion 16 may be provided with a separately formed cheek piece 57 which is fastened against the outer face of the block by suitable means; bolts 58 for example. Notches 44, similar to those in cheek-piece 37

may be formed therein, and also a circular groove 42 similar to that in said cheek piece may be provided for receiving an edge portion of the facing strip 20.

To facilitate assembly one end of the spindle 5 may be threaded as indicated at 60, and a threaded nut 61 provided thereon. A shoulder 63 is advantageously formed on the spindle, to sustain the thrust of the nut 61.

To replace one or more worn tires 18, 19, 20 (strips 25) the nut 61 is loosened so as to release the block 12. The block 12 is then slid longitudinally thereby allowing separation of the block from a cheek-piece or from the cheek pieces 36, 37, 38. It is most efficient in replacing the tires to remove the block with cheek pieces 37, 38 thereon. The cheek piece 37 may then be slid off of the cylindrical section 14 carrying the tire 18 with it. Then the cheek piece 37 may be slid off of the cylindrical portion 15 carrying the tire 19 with it. The tire 18 is then free to be slid off of the cylindrical portion 16.

In practice when it is necessary or desirable to replace one tire, it would be well to replace all of the tires. To do so a new tire 20 is placed on the cylindrical portion 16 and the edge having the notches 30 therein slid into the groove 42 of the cheek-piece 57 so that the pins or projections 33 fit into the said notches. The cheek piece 38 is then placed on the cylindrical portion 15 and slid against the tire 20 so that the adjacent edge thereof enters the groove 50 and bears against the bottom of the groove. A tire 19 is then placed on the cylindrical portion 15 and its edge having the notches 30 therein, slid into the groove 42 with the pins 33 entering the notches 30. The cheek piece 37 is then slid over the cylindrical portion 14 and against the adjacent edge of the tire 19 so that the edge enters the groove 50 therein. The tire 18 is then placed on the cylindrical portion 14 and the edge portions of the tire 18 entered into the grooves 42 and 55 of the opposite cheek pieces 37 and 36. The nut 61 is then tightened against the block 12. The pressure of the nut forces the tire 18, 19 and 20 against the bottoms of the grooves in the respective cheek pieces. The pressure is transmitted through the tires and cheek pieces to the cheek piece 53, which bears against the shoulder 63 on the spindle, the bearing as here shown being through a collar 70 and an inner ring of a ball bearing 75. In the fully seated position of the tires 18, 19 and 20 there is advantageously a slight clearance between the sides of the cheek pieces and the sides of the block as indicated at 65 so that the thrust of the nut 61 on the block 12 will be transmitted through the tires 20, 19 and 18 and the cheek-piece 38 to the cheek piece 37 which sets against the shoulder 63, the seating as here shown, being through the collar 70 and the inner ring of the ball bearing 75. The undercut grooves 42, 50 assure the firm seating of the tire-strips 25 on the respective cylindrical portions 14, 15, 16 of the drum, or to be pressed firmly thereagainst if not so seated at the time of assembly. The foregoing construction and arrangement provides a simple way of assembling the separated parts and holding them tight in assembled position. However, the cheek pieces could be held against the sides of the block and against the edges of the tire strips otherwise than through the action of the nut 61 and the joint action of the tires and cheek pieces.

The pulleys or blocks may serve for other uses

than that described and the invention may receive other embodiments than that herein specifically illustrated and described.

What is claimed is:

- 5 1. A capstan block or the like, comprising a cylindrical portion and a replaceable tire on said cylindrical portion, with which wire makes contact, said replaceable tire being a flat strip of wear resisting metal having a length slightly less than the circumference of said cylindrical portion when fitted closely thereon, so that each 5 strip may lengthen slightly without buckling under thermal expansion, cheek-pieces at opposite sides or edges of each tire-strip, a plurality of said cheek-pieces being separable, and having central openings corresponding in diameter to 10 the diameters of said cylindrical portions, said part having said cylindrical portions thereon and said cheek-pieces being movable axially of said arbor, said cheek-pieces having circular grooves into which the opposite sides or edges of said tire- 15 strips extend so that the marginal portions of said tire-strips are covered by said cheek-pieces, each of said grooves in said cheek-pieces having its wall which is closest to the axis of the drum of a diameter less than the diameter of the cylind- 20 rical portion of the block on which the respective tire-strip bears, so that each of said tire- strips may bear firmly and uniformly on its cylindrical portion, the marginal portion of each tire-strip within the area covered by a cheek- 25 piece, having notches therein, and projections covered by said cheek-pieces, extending into said notches, for preventing slip between said tire-strip and the cylindrical portion on which it bears.
- 30 2. A capstan block according to claim 1, wherein said block has a plurality of cylindrical portions of different diameters thereon, and further comprising a plurality of cheek-pieces having central openings having diameters corresponding to the diameters of the plurality of said cylindrical portions of the block, said cheek-pieces having grooves on opposite sides thereof of different diameters into which edges of tire strips on cylindrical portions of different diameter fit.
- 35 3. A capstan block or the like, comprising an arbor, a shoulder on said arbor, a part having a plurality of cylindrical portions of different diameter, and a replaceable tire on each of said

cylindrical portions with which wire makes contact, said replaceable tires each being a flat strip of wear resisting metal having a length slightly less than the circumference of its cylindrical portion when fitted closely thereon, so that each 5 strip may lengthen slightly without buckling under thermal expansion, cheek-pieces at opposite sides or edges of each tire-strip, a plurality of said cheek-pieces being separable, and having central openings corresponding in diameter to 10 the diameters of said cylindrical portions, said part having said cylindrical portions thereon and said cheek-pieces being movable axially of said arbor, said cheek-pieces having circular grooves into which the opposite sides or edges of said tire- 15 strips extend so that the marginal portions of said tire-strips are covered by said cheek-pieces, each of said grooves in said cheek-pieces having its wall which is closest to the axis of the drum of a diameter less than the diameter of the cylind- 20 rical portion of the block on which the respective tire-strip bears, so that each of said tire- strips may bear firmly and uniformly on its cylindrical portion, the marginal portion of each tire-strip within the area covered by a cheek- 25 piece, having notches therein, and projections covered by said cheek-pieces, extending into the notches in the marginal portions of each of said tire-strips, for preventing slip between said tire- strips and the cylindrical portions on which they 30 bear, each of said tire-strips having a width exceeding the width of the cylindrical portion on which it bears plus the depth of each groove into which its marginal or edge portions extend, so as to provide a clearance between each cheek- 35 piece and the side of the cylindrical portion adjacent thereto, and a nut on said arbor acting against said part having the cylindrical portions thereon to transmit thrust through the assembled tire-strips and cheek-pieces to said shoulder 40 on said arbor.

CARL O. BRUESTLE.
